CLAIM

I claim the ornamental design of a bridge for pince nez eyewear, as shown and described.

DESCRIPTION

FIG. 1 is a perspective view of the bridge for pince nez eyewear;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right view thereof.

The broken lines shown in FIGS. 1-7 are for illustrative purposes only and form no part of the claimed design.

1 Claim, 6 Drawing Sheets(56)
